HAND VISE OF THE LEVER-AND-PLUNGER-OPERATED SLIDING-JAW TYPE

Harm D. Snell, Port Arthur, Tex., assignor of twenty-five per cent to Joann Snell, Port Arthur, Tex.

Application November 18, 1947, Serial No. 786,699

2 Claims. (Cl. 81—26)

1

My invention relates to improvements in vises of the lever-and-plunger-operated sliding-jaw type.

The primary object of my invention is to provide in a hand vise having a fixed jaw, a movable jaw, and a carriage for advancing and retracting the movable jaw, improved means for advancing the movable jaw relative to the carriage to tighten the movable jaw against the work, and which is operative by swinging movement of a hand lever on the carriage and by a plunger in the hand lever operative by a hand grip section feedable on and along the hand lever, and whereby a vise is achieved which is better suited for clamping easily bruised and crushed work, for instance, wood, without mutilating the same.

Another object is to provide a vise of the type and for the purpose above set forth which involves few parts, to provide a vise of inexpensive construction, and one which will not quickly get out of order from prolonged use.

Other and subordinate objects also, within the purview of my invention, together with the precise nature of my improvements will be readily understood when the succeeding description and claims are read with reference to the drawings accompanying and forming part of this specification.

In said drawings:

Figure 1 is a view in side elevation of my improved vise, in a preferred embodiment thereof, partly broken away;

Figure 2 is a view in plan, partly broken away;

Figure 3 is a view in longitudinal section taken on the line 3—3 of Figure 2;

Figure 4 is a fragmentary view in transverse section taken on the line 4—4 of Figure 1;

Figure 5 is a view in transverse section taken on the line 5—5 of Figure 1 and drawn to a larger scale; and

Figure 6 is a view in longitudinal section taken on the line 6—6 of Figure 2 and drawn to a larger scale.

Referring to the drawings by numerals, my improved vise, as illustrated, comprises an elongated plate 1 with a front end 2 widened for strength, longitudinal parallel side edge grooves 3 therein, for a purpose presently seen, and a reduced, coplanar rear end handle 4.

A fixed jaw 5 is secured, in any suitable manner (not shown) on the front end 2 of said plate 1 at a right angle to what constitutes the working face 6 of said plate, and which extends completely across said end 2.

1 A longitudinal row 7 of ratchet teeth is provided in the longitudinal center of said plate 1 flush with said working face 6 and the purpose of which will presently become apparent.

5 A movable jaw 8 straddles the plate 1 transversely thereof and extends across said working face 6 for coaction with the fixed jaw 5, said movable jaw 8 being slidably connected to said plate 1 for advance and retraction along said plate 1 into and from clamping relation to the fixed jaw 5. The connection between the movable jaw 8 and said plate 1 takes the form of inturned guide ribs 9 (see Figure 4) on said jaw 8 slidably fitted in the beforementioned grooves 3.

10 A movable carriage 10 for the movable jaw 8 straddles said plate 8 transversely thereof in the rear of said movable jaw and is slidably connected to said plate 1 for advance and retraction with said movable jaw. The slideable connection for the carriage 10 also takes the form of guide ribs 11 (see Figure 5) on said carriage fitted in said grooves 3.

15 A pair of bolts 12 extend through the movable carriage 10 near opposite sides thereof and are threaded into the movable jaw 8 with rear end kerfed heads 13 thereon slideable in bores 14 provided in said carriage 10.

20 A pair of bolts 12 extend through the movable carriage 10 near opposite sides thereof and are threaded into the movable jaw 8 with rear end kerfed heads 13 thereon slideable in bores 14 provided in said carriage 10.

25 Coil springs 15 in said bores 14 and on said bolts 12, interposed between said heads 13 and the front ends of said bores 14, urge said bolts 12 rearwardly to normally urge the movable jaw 8 toward the movable carriage 10.

30 A plate-like pawl 16 is pivotally mounted on the movable carriage 10, at the rear thereof, to ratchet over the ratchet teeth 7 during advance of said carriage 10 and hold said carriage advanced, and is spring pressed by a suitable spring 17 to engage said teeth 7. The mounting for said pawl 16 comprises an attaching hinge plate 18 set into the bottom of the movable carriage 10, and bolted thereto by screws, as at 19. A finger 20 on said pawl 16 provides for manually swinging the same into idle position.

35 A hand lever designated as a unit by the numeral 21 is provided on the movable carriage 10 and comprises a tubular front shank section 22 having a forked front end 23 pivoted by screw studs 24 between a pair of ears 25 on top of said carriage 10 so that said shank section 22 is swingable toward and from the plate 1, respectively, about an axis transverse to the line of movement of said carriage 10.

40 A tubular hand grip section 26 with a rear end closed by a screw plug 27 is threaded onto the 50 rear end of said shank section 22 for feeding for-

3

wardly and rearwardly thereon for a purpose presently seen.

A plunger rod 28 is fitted in said shank section 22 to extend forwardly beyond the forked end 23 of said section and rearwardly out of said section into the hand grip section 26, and is endwise slideable in said shank section 22. The plunger rod 28 has a front end eye 29 pivotally connected by a transverse pin 30 between a pair of ears 31 on a motion-compensating link 32 pivoted by a pin 33 in the rear side of the movable jaw 8. The pins 30, 33 provide pivotal axes for the front end of said rod 28 and said link 32 parallel to the pivotal axis of the shank section 22. As will be seen, the eye 29 and pin 30 form a joint between the front end of the lever 21 and the movable jaw 8, permitting swinging of said lever toward and away from the plate 1 in connection with said movable jaw, said joint assuming a dead center position relative to the axis of movement of the link 32 and the shank section 22 when said hand lever 21 is in an intermediate position. In this connection, a rear shoulder 34 on the movable carriage 10 engages the shank section 22 to limit movement of said hand lever 21 toward the plate 1, and a front shoulder 35 on said carriage 10 similarly limits movement of said lever 21 away from said plate 1.

Referring now to the use and operation of the described vise: With the hand grip section 26 of the hand lever 21 backed off on the shank section 22, sufficiently, and said hand lever 21 swung into its limit of movement away from the plate 1, the coil springs 15 act to retract the bolts 12 in the bores 14, and thereby hold the movable jaw 8 against the front of the movable carriage 10. By shoving the movable carriage 10, through the medium of the hand lever 21, forwardly, the movable jaw 8 will be slid to advance the same into engagement with a piece of work, as shown in dotted lines at 36 in Figures 1 and 2, as interposed between the fixed and movable jaws 5, 8. During this operation, the pawl 16 will idle over the ratchet teeth 7. Now, by shoving forwardly on the hand lever 21 and swinging the same into its limit of movement toward the plate 1, the movable carriage 10 will be backed off from the movable jaw 8 when the pivot pin 30, or the previously described joint, assumes dead center relation to the pins 24, 33, until the pawl 16 locks against a ratchet tooth 7. This locks the movable jaw 8 in approximate, loose clamping position to the piece of work 36. By turning the hand grip section 26 forwardly on the shank section 22, thus causing the plunger rod 28 to be thrust forwardly in the shank section 22, the movable jaw 8 may be forced into tight clamping relation to the piece of work 36, as desired. By swinging the pawl 16 into idle position, through the finger 20, the movable carriage 10 will be unlocked for retraction of the movable jaw 8, in a manner which will be clear, out of clamping relation to the piece of work 36.

The foregoing will, it is believed, suffice to impart a clear understanding of my invention, without further explanation.

4

Manifestly, the invention, as described, is susceptible of modification, without departing from the inventive concept, and right is herein reserved to such modifications as fall within the scope of the appended claims.

Having described the invention, what is claimed as new is:

1. In a work piece clamping vise of the class described, a plate having a working face and a fixed jaw on said face, a clamping assembly including a movable jaw, said clamping assembly being slidably mounted on said plate for advance over said working face to engage the movable jaw with the work piece interposed between said jaws and to loosely clamp the work piece therebetween, a hand lever pivotally connected to said clamping assembly for swinging movement relative thereto and including a hand grip section threaded thereon for feeding along the same, means operative by swinging movement of said lever to lock said clamping assembly against retraction after engagement of the movable jaw with the work piece, and means operative by feeding movement of said hand grip section to advance said movable jaw in the locked position of said clamping assembly for tight clamping engagement of said movable jaw with the work, the last-mentioned means including a plunger rod slideable in said hand lever, and a toggle link connecting said rod and said movable jaw.

2. In a work clamping vise of the class described, a plate, a fixed jaw on said plate, a clamping jaw assembly comprising a carriage slidably mounted on said plate for movement toward or away from the fixed jaw, a jaw slidably mounted on said carriage for movement toward or away from said fixed jaw independently of movement of said carriage, a hand lever on said carriage for pushing the same to advance said carriage and movable jaw in unison, said hand lever being pivoted on the carriage for swinging movement with respect thereto, means sequentially operative by swinging movement of said hand lever to lock said carriage to said plate and to advance the movable jaw, said means including a plunger rod mounted in said hand lever and swingable therewith, and slideable in the hand lever to still further advance the movable jaw independently of the carriage, and a hand grip member feedable along said hand lever to slide said plunger.

HARM D. SNELL.
